UNITED STATES PATENT OFFICE.

FRED E. NORTON, OF WORCESTER, MASSACHUSETTS, ASSIGNOR TO JEFFERIES-NORTON CORPORATION, A CORPORATION OF DELAWARE.

PROCESS OF REFRIGERATION.

1,264,845.

Specification of Letters Patent. Patented Apr. 30, 1918.

Application filed March 3, 1915. Serial No. 11,850.

To all whom it may concern:

Be it known that I, FRED E. NORTON, a citizen of the United States, residing at Worcester, in the county of Worcester and Commonwealth of Massachusetts, have invented a new and useful Improvement in Processes of Refrigeration, of which the following, together with the accompanying drawings, is a specification.

10 The present invention relates to processes of refrigeration, and has particular reference to improvements in processes of this class which, in general, contemplate the attainment of extremely low temperatures by the expansion of a gaseous fluid. The low temperatures attained in the present process, in common with the processes previously practised, may be used, if desired, in securing extreme refrigerative effects; or the 15 process may be carried on for the purpose of liquefying, in whole or in part, the gas, and if desired, this liquefaction, if the gas be a mixed gas, may be employed in connection with suitable distillation agencies to effect 20 the separation of the gas into its constituent elements. Moreover, as will be shown, the process may with advantage be utilized for the cheap and efficient production of power, in a form available for the production of 25 useful work.

25 The process of the present invention contemplates the attainment of marked improvements in efficiency and capacity over refrigeration systems using the processes heretofore known; the principles of the invention and the various steps employed in the application of said principles to the accomplishment of the desired results, are fully set forth in the following description 30 and pointed out in the annexed claims, reference being had to the accompanying drawings, which illustrate, diagrammatically, one arrangement of apparatus for carrying out said steps.

35 In the said drawings, wherein like reference characters are used to indicate like parts in the several views,

Figure 1 is a diagrammatic representation of an arrangement of apparatus which may be employed.

Fig. 2 is a fragmentary portion of the same apparatus, shown on an enlarged scale, and

Fig. 3 is a view similar to Fig. 2, showing

a modification of the apparatus illustrated 55 therein.

It is to be understood, however, that the carrying out of my invention is not confined to the employment of the herein described, or any other particular arrangement of apparatus, nor to the herein described methods of operating such apparatus, except in so far as specified in the appended claims; the drawings and description being illustrative merely of one way of applying the principles of my invention.

As heretofore practised, processes of this class, which may or may not involve the complete liquefaction of the working fluid, depending upon the ultimate purpose to 70 which the refrigeration is to be applied, have shown extremely low efficiency and capacity for refrigeration, by reason of the demands made upon the external cooling agency in attaining the desired low temperatures, such systems, therefore, requiring large expenditures of power for supplying the necessary refrigerative effect. In such prior processes it is customary to cool the incoming compressed working fluid by interchange of heat with cold expanded working fluid flowing countercurrent thereto, thereby bringing said incoming fluid into a condition to be liquefied by the cooling effect of the external cooling agency. It is known that 85 the specific heat, and hence the heat absorbing capacity, of a cold compressed gas is greater, the higher the pressure upon said gas; in such prior processes, therefore, it is apparent that the cooling effect of the expanded low pressure gas flowing countercurrent to the incoming highly compressed gas, is subject to serious limitations by reason of 90 this phenomenon; in other words, it is manifestly impossible for a given weight of incoming working fluid under high pressure, to be cooled through the same range of temperature as the same weight of outgoing low pressure gas is warmed, by the interchange 95 of heat above described. As a result, this deficiency in cooling effect must be compensated for by the external cooling agency, 100 greatly reducing the latter's ability to produce useful or available refrigerative effect.

It has heretofore been proposed, in processes of this class, to retain the outgoing working fluid under pressure, and even to increase its pressure over the pressure under 105

which it was liquefied, as fully set forth in the process described in the copending application of E. A. W. Jefferies, Serial No. 4536, filed January 26, 1915, whereby 5 said outgoing fluid after leaving the system is capable of efficiently absorbing external heat, for the performance of useful work by expansion. However, since the external cooling agency, which is essential to 10 the process of said copending application, is alone relied upon to effect the liquefaction of the incoming gaseous fluid, i. e., to remove its latent heat, said liquefaction must be accomplished under such a high 15 pressure, that an increase of pressure sufficient to yield any considerable advantage from the above described specific heat phenomenon is both impracticable and undesirable.

20 According to the present invention the difficulties above enumerated are overcome by the employment of certain steps designed to effect the extraction of latent heat from the incoming working fluid, whereby a 25 great part of the burden of cooling heretofore imposed on the external cooling agency is relieved, and the liquefaction of the incoming fluid can be accomplished under a relatively low pressure. As a result of the 30 above, a considerable pressure increase upon the outgoing portion of the working fluid is permissible; the consequent relatively high heat absorbing capacity of the outgoing fluid can be utilized for the extraction 35 of heat from the low pressure incoming fluid and for absorbing the inleakage of external heat, and the efficiency and capacity of the entire system thus correspondingly increased.

40 With reference to the application of these principles to the attainment of the objects hereinbefore mentioned, the diagrammatic illustration of one arrangement of apparatus for carrying out the process, together 45 with the several steps of the process, will now be described in detail.

Referring, by way of example, to the accompanying drawings, the gas dealt with in my process is compressed in a compressor 50 1, and is then led through an ordinary water cooling device 2, for the purpose of extracting the heat of compression therefrom. From the cooling device 2, the compressed gas passes into a passage 3 of a heat ex- 55 changer, designated as a whole by the numeral 4. A portion of the gas in passage 3 is led to an expansion engine 5, expanded therein and returned to the hold end of a second passage 6 of the heat exchanger 4, as 60 shown by the arrows, Fig. 1. Said expansion engine 5 and passage 6 are part of an external cooling agency; the circulation of a portion of the working fluid through such agency is utilized in extracting a portion 65 of the heat from the incoming compressed

fluid in the passage 3, and in offsetting the inleakage of atmospheric heat, in the manner common to liquefying processes at present in use.

The lower end of the passage 3 serves as 70 a container for a quantity of the working fluid which is liquefied within said passage in the manner hereinafter set forth; there is no escape for such liquid to the return circuit of the system except through a pump 75 7, which delivers the liquid into a third passage 8 of the heat exchanger 4 at a pressure higher than the pressure in passage 3. The pressure prevailing in the passage 8 is obviously due to the resistance imposed 80 against the outflow of vapor from the upper end of said passage; in forcing liquid into the bottom of this passage, the pump 7 must put it under sufficient pressure to 85 overcome the pressure prevailing therein, 90 which, as above stated, is higher than the pressure prevailing in passage 3. The heat exchange between the fluids in passages 3 and 8, in a manner similar to that well-known in apparatus of this character, entails the discharge of high pressure fluid 95 from the top or warm end of passage 8 at substantially the temperature of the gas entering the interchanger at the top or warm end of passage 3; the substantial equalization of temperatures at any given level by heat interchange between the two passages 3 and 8, is contemplated, and in common with other apparatus of this character, the temperatures are lower, the lower the level 100 reached in said interchanger. In said passage 8 the liquid is evaporated and has its temperature raised, in the manner herein-after particularly described; from the passage 8 the highly compressed evaporate may 105 be led, as described in the aforesaid copending application of Jefferies, either with or without the addition of external heat to a motor 9 wherein it may be used to develop 110 a portion of the power for driving the compressor 1. If desired, the gas exhausted from said motor and the gas from the external cooling agency leaving the warm end of the passage 6 of the interchanger may 115 be returned to the inlet of the compressor 1, recompressed therein and passed again through the same circuits.

Assuming the establishment of the conditions illustrated in Fig. 1, wherein the broken lines indicate the presence of the 120 working fluid in a liquefied state, which condition may be attained, if desired, by the operation of the external cooling agency above described, it will be clear especially if the fluid dealt with is a simple gas, that the 125 natural interchange of heat between the cold compressed gas at the point of liquefaction in passage 3 and the liquid in passage 8 will not effect the liquefaction of said gas in passage 3, nor will it effect the evaporation 130

of said liquid in passage 8, since the condensation temperature in passage 3 is lower than the boiling temperature in passage 8, owing to the difference in pressure produced by the 5 pump 7. The transfer of the latent heat of condensation from the vapor being condensed above surface *a* to evaporate the liquid at *b*, is effected in the manner shown in Fig. 2, wherein 10 represents a coil immersed in the liquid formed within the passage 3 of the interchanger and 11 represents a pump or compressor interposed between said coil 10 and a coil 12 immersed 10 in the liquid contained within the passage 15 8 of the interchanger. Said coil 12 communicates with an expander or nozzle 13, and the latter is connected to the inlet side of the coil 10, thereby forming a closed circuit. Said circuit may be supplied with a circulating 20 fluid having a boiling point at the same or a lower temperature than the fluid to be condensed at the surface *a*. Assuming that the compressor 11 works at a slightly higher pressure than the pump 7, and that 25 the fluid used in said circuit is the same as the working fluid, it will be clear that the circulation by compressor 11, during a given period, of a weight of fluid equal to or slightly in excess of the weight of working 30 fluid entering passage 3 during the same period, will effect this transfer of heat contents, as follows:—The fluid passing to coil 10, after its pressure is released in nozzle 13, may be mostly liquid, and while condensing 35 the fluid above surface *a*, by extracting the latent heat of condensation therefrom, it may be only partly evaporated. The mixture of liquid and vapor from the coil 10, passing to the compressor 11, has its pressure 40 and temperature raised by said compressor. Passing in substantially gaseous form to the coil 12, it effects the evaporation of liquid at the surface *b*, by transfer of its heat to said liquid, and is itself condensed thereby, 45 in whole or in part. The subsequent release of pressure from said circulating fluid in the nozzle 13 and the consequent recooling thereof, causes its return to the coil 10 in condition to repeat the condensation at the surface *a*, in the manner above described. 50 The actions, above described, will be carried out, under the conditions assumed, very readily, merely by causing the liquid in coil 10 to be slightly colder than the low pressure working vapor to be liquefied at this point, in order to promote the transfer of heat contents in the proper direction; and it will be seen that the difference in temperature relied upon to effect this transfer of heat units between the fluids can be made as small as desired simply by increasing the contact surfaces of the coil. The same is obviously true of the action occurring in the high pressure passage 8, in which a slightly higher temperature within the coil 12 insures the neces-

sary exchange of latent heats. It will be clear that other conditions affecting the pressure, temperature, composition, and quantity of the circulatory transfer fluid may be adopted, within a wide range, without departing from the principles of the actions above set forth, since the foregoing assumptions were made merely for purposes of explanations. As has been shown, the transfer of the relatively large quantities of heat 70 between the working and the circulating fluids occurs in each case with only a very slight temperature difference; that is to say, the absorption and rejection of latent heat by the working and circulating fluids, as described above, takes place under substantially constant temperature and hence with the highest possible efficiency. 75

The condensation of the fluid at the surface *a* is, therefore, secured by an evaporation 80 of circulating fluid in the coil 10, and the evaporation of the liquid at the surface *b* is secured by a condensation of circulating fluid in coil 12. It is apparent that by the proper adjustment of the pressures in the 85 coils 10 and 12, and of the quantity and nature of fluid circulated through said coils by the compressor 11, the relative proportion of liquid and gaseous content of the fluid in said coils may be controlled so as to attain 90 the most efficient transfer of latent heat of condensation from the fluid in passage 3 to the liquid in passage 8, namely, in such a manner that the quantity of fluid condensed at *a* may equal the quantity of liquid evaporated at *b*. 95

A modification of the transferring means, shown in Fig. 3, involves the omission of the coil 12, the fluid from compressor 11 being discharged directly into the liquid contained 100 in the passage 8. Under these circumstances, only liquid passes to the nozzle 13, while the compressor 11 returns only vapor, which may be at a sufficiently high temperature to cause the evaporation of an equal 110 amount of fluid from the liquid at *b*, while being itself completely condensed.

The return of the cold vaporized fluid through the passage 8 at a higher pressure than the incoming fluid in passage 3, secures 115 a most efficient cooling of said incoming fluid, by reason of the increased specific heat of the returning fluid. Owing to its greater pressure and increased specific heat, said re-evaporated fluid carries out from the system 120 a greater amount of heat per degree of temperature exchanged than is brought in by the same weight of fluid from the compressor. As a result, the subsequent liquefaction 125 of said incoming fluid, at the surface *a*, is effected with greater facility than in the processes now in ordinary use. Such liquefaction is promoted, or wholly brought about, by the above described transfer of the latent heat of condensation of the fluid in 130

passage 3 to the liquid in passage 8. The cooling which must be done by the refrigerating or expansion circuit containing the expansion engine 5 (which is not qualified for the most efficient heat extraction owing to the extremely low pressure of the cold gas returning in passage 6) is reduced to a minimum; however, the drop in temperature in the expansion engine 5, when the latter is 5 suitably constructed, can be made so great as to cause a partial condensation of fluid in the exhaust therefrom which may be collected in the cold end of passage 6.

The added refrigerative effect resulting 15 from the process may be utilized in various ways; cold vapor for refrigeration may be withdrawn at 14, or liquid may be withdrawn at 15. By means of bypass 16 and valve 17, the liquid in passage 3 may be reduced in pressure and drawn out at 15, or 20 the same may be drawn out, under pressure at 18.

It is to be understood that the process, as herein described, does not of necessity entail either the complete or the absolute liquefaction of the gaseous working fluid, and that the terms "liquefaction," "liquid" and "liquefied" as used herein and in the appended claims apply as well to a condition 25 of the fluid where in density and temperature it substantially approaches the liquid state. In such a condition said fluid is susceptible to a pressure increase by the expenditure of an almost negligible amount of 30 power, which, together with the power required for initial compression is largely recoverable in the efficient manner hereinbefore set forth.

The same of course holds true with respect 40 to the changes in state undergone by the circulating latent heat transfer fluid, which, corresponding substantially in density and in coldness to the working fluid is compressed by the expenditure of an amount of 45 work which is exceedingly small in comparison to the work of cooling that would otherwise have to be expended in the external cooling agency to remove the latent heat from the incoming working fluid.

50 In the application of the foregoing new principles, which differ radically and essentially from the principles underlying previous processes of this class, it is to be understood that my invention is in no sense limited to equivalents of the apparatus herein shown, said showing being wholly diagrammatic and illustrative and adopted solely for the purpose of simplifying the explanation of said broadly new principles.

60 I claim,

1. In a process of refrigeration, employing a working fluid which is gaseous in its free state, the counter-current circulation of said working fluid to effect heat interchange between heat absorbing and heat rejecting

portions thereof, and the increase of the capacity of said heat absorbing portion by increase of its specific heat.

2. In a process of the class described, the progressive liquefaction of a fluid which is 70 gaseous in its free state, by the extraction of the latent heat therefrom, and the transfer of said latent heat to the liquefied fluid after the pressure thereon has been raised.

3. In a process of the class described, involving the progressive liquefaction of a fluid which is gaseous in its free state, the raising of the liquefied fluid to a pressure greater than that at which it was liquefied, and the vaporization of said liquefied fluid 80 under such increased pressure by means of the latent heat of the fluid undergoing liquefaction.

4. In a process of the class described, involving the progressive liquefaction of a 85 fluid which is gaseous in its free state, the raising of the liquefied fluid to a pressure greater than that at which it was liquefied, the vaporization of said liquefied fluid under such increased pressure by means of 90 the latent heat of the fluid undergoing liquefaction, and the circulation of said evaporate in heat exchanging relation to the fluid about to be liquefied.

5. In a process of the class described, the 95 progressive liquefaction of a fluid which is gaseous in its free state, by the compression of said fluid, the expansion of a portion of said compressed fluid, the extraction of latent heat from another portion of said 100 compressed fluid to liquefy the same, the raising of the pressure on the fluid thus liquefied, the evaporation of the liquefied fluid under such increased pressure by means of said latent heat, and the circulation of 105 said evaporate and said expanded portion of the fluid in heat exchanging relation to the compressed fluid about to be liquefied.

6. In a process of the class described, involving the progressive liquefaction of a 110 fluid which is gaseous in its free state, the raising of the liquefied portion of the fluid to a pressure greater than that at which it was liquefied, and the liquefaction of the gaseous portion under the lower pressure by 115 transfer of its latent heat to said liquefied portion under the higher pressure.

7. In the herein described process of refrigeration, employing a liquefied gas, the extraction of the latent heat of condensation from the gas undergoing liquefaction by heat exchange with a circulating fluid, raising the pressure of said circulating fluid after such extraction, and transferring the extracted heat to the liquefied gas after the 125 pressure on said liquefied gas has been raised.

8. In the herein described process of refrigeration, employing a liquefied gas, the extraction of the latent heat of condensation 130

from the gas undergoing liquefaction by exchange of heat with a circulating fluid, raising the pressure on said circulating fluid after such extraction, condensing said circulating fluid by transfer of the heat previously absorbed thereby to the liquefied gas produced by the process, after the pressure on said liquid has been raised, and reducing the pressure on said circulating fluid to the initial pressure.

9. In the herein described process of refrigeration, employing a liquefied gas, the extraction of the latent heat of condensation from the gas undergoing liquefaction by heat exchange with a circulating fluid, raising the pressure of said circulating fluid after said extraction, and transferring the heat absorbed thereby to the liquid produced by the process after the pressure of said liquid has been raised.

10. The herein described process of refrigeration, comprising the extraction of latent heat from a fluid undergoing condensation by heat exchange with an independent circulating fluid, and the transfer of said latent heat to the first fluid at higher pressure undergoing evaporation.

11. The herein described process of refrigeration, comprising the extraction of latent heat from a fluid, at a low temperature, by heat exchange with an independent circulating fluid, and the transfer of said extracted heat to the first fluid at a higher temperature.

12. The herein described process of refrigeration, comprising the extraction of latent heat from a fluid undergoing condensation by heat exchange with a circulating fluid, and the transfer of said latent heat to the first fluid at a higher pressure undergoing evaporation.

13. The herein described process of refrigeration, comprising the extraction of latent heat from a fluid, at a low temperature, by heat exchange with a circulating fluid, and the transfer of said extracted heat to the first fluid at a higher temperature.

14. The herein described process of refrigeration, comprising the extraction of latent heat from a fluid at a low temperature, and the transfer of said extracted heat to said fluid at a higher temperature, by interchange of heat with a circulating fluid which undergoes changes of pressure, and whose boiling point at the lower pressure is at a lower temperature than the fluid from which heat is extracted, and whose condensing point at the higher pressure is at a higher temperature than the fluid to which the heat is added.

15. In a process of the class described, involving the progressive liquefaction of the fluid which is gaseous in its free state, the raising of the liquefied fluid to a pressure greater than that at which it was liquefied,

and the transfer of latent heat of condensation from the gaseous portion undergoing liquefaction to said liquefied portion under the increased pressure by the circulation of a fluid in heat exchanging relation to said two portions.

16. In a process of the class described, involving the progressive liquefaction of a fluid which is gaseous in its free state, the raising of the liquefied fluid to a pressure greater than that at which it was liquefied, and the transfer of latent heat of condensation from the gaseous portion undergoing liquefaction to said liquefied portion under the increased pressure by the alternate compression and expansion of a fluid circulated in heat exchanging relation to said two portions.

17. In a process of the class described, involving the progressive liquefaction of a fluid which is gaseous in its free state, the raising of the liquefied fluid to a pressure greater than that at which it was liquefied, the vaporization of said liquefied fluid under such increased pressure by means of the latent heat of the fluid undergoing liquefaction, and the utilization of the vapor thus produced to furnish power.

18. In a process of the class described, involving the progressive liquefaction of a fluid which is gaseous in its free state, the raising of the liquefied fluid to a pressure greater than that at which it was liquefied, the vaporization of said liquefied fluid under such increased pressure by means of the latent heat of the fluid undergoing liquefaction, the circulation of said evaporate in heat exchanging relation to the fluid about to be liquefied, and the expansion of said evaporate to produce power.

19. In a process of the class described, extracting latent heat from a fluid undergoing liquefaction by means of another fluid, raising the pressure on the liquefied fluid and on the second fluid, and circulating said second fluid under its increased pressure in heat exchanging relation to the high pressure liquefied fluid.

20. In a process of the class described, extracting latent heat from a fluid undergoing liquefaction by means of another fluid, raising the pressure on the liquefied fluid and on the second fluid, circulating said second fluid under its increased pressure in heat exchanging relation to the high pressure liquefied fluid, to evaporate the latter, and expanding said evaporate in an expansion engine.

21. In a process of the class described, extracting latent heat from a fluid undergoing liquefaction by means of another fluid, and vaporizing the liquefied fluid, by means of said other fluid, under a sufficient pressure to enable the evaporate to perform useful work by expansion.

22. In a process of the class described, extracting latent heat from a fluid undergoing liquefaction by means of another fluid, vaporizing the liquefied fluid by means of said 5 other fluid, under a sufficient pressure to enable the evaporate to absorb heat usefully, and expanding said evaporate in an expansion engine.

23. In a process of the character set forth, 10 employing a working fluid which is gaseous in its free state, the passage of said fluid through the liquid state, and the transfer of latent heat from the gaseous working

fluid to the portion thereof which is in the liquid state.

24. In a process of the character set forth, the passage of a gaseous working fluid through the liquid state, the increase of pressure thereon while in the liquid state, and the transfer of latent heat from the gaseous 20 fluid to the liquid whose pressure has been raised.

FRED E. NORTON.
